UNITED STATES PATENT OFFICE.

RUDOLF KRON, OF GOLZERN, SAXONY, GERMANY.

SEPARATING APPARATUS FOR PAPER-PULP, &c., SUSPENDED IN LIQUIDS.

SPECIFICATION forming part of Letters Patent No. 365,343, dated June 21, 1887.

Application filed January 25, 1887. Serial No. 225,456. (No model.) Patented in England November 11, 1886, No. 14,603; in France November 11, 1886, No. 166,786; in Austria-Hungary November 11, 1886; in Belgium November 11, 1886; in Germany November 12, 1886, No. 5,188, and in Italy December 2, 1886, XX, 20,760.

To all whom it may concern:

Be it known that I, RUDOLF KRON, a citizen of the Republic of Switzerland, residing at Golzern, Kingdom of Saxony, Germany, have 5 invented certain new and useful Improvements in a Separating Apparatus for Paper-Pulp and other Substances Suspended in Liquids, of which the following is a specification, and in which—

10. Figure 1 is a longitudinal vertical sectional view of my improved machine for separating or straining fluids from solids. Fig. 2 is a transverse sectional view of the same. Fig. 3 is a longitudinal vertical sectional view of a 15 modified form of the machine. Fig. 4 is a similar view of another modification. Fig. 5 is a similar view of still another modification, and Figs. 6 and 7 are respectively a longitudinal vertical sectional view and a transverse 20 sectional view of another modified form of the machine.

Similar letters of reference indicate corresponding parts in all the figures.

My invention has relation to machines for 25 separating granular or fibrous solid bodies suspended in fluids from the said fluids; and it consists in the improved construction and combination of parts of such a machine, in which a comparatively large straining-surface 30 is obtained in a small space, and in which the straining-surface may be beaten or vibrated for the purpose of preventing clogging of the apertures in the same, the machine being especially adapted for straining paper-pulp, cel- 35 luloid-pulp, or coloring materials dissolved in water, as hereinafter more fully described and claimed.

In the accompanying drawings, the letter A indicates a tank or box having a suitable out- 40 let, f, and having a straining-bottom, S, of a suitable perforated material, dividing the tank or box into an upper and a lower compartment, respectively lettered a' and a''. The straining-bottom is shaped with corrugations 45 of different shapes, the corrugations shown in Figs. 1 and 2 being triangular in section, the corrugations shown in Fig. 3 being waved, in Fig. 4 cog-shaped or rectangular, and in Fig. 5 triangular with open upper edges, and a 50 beater, B, is suspended below the bottom, and

is formed with suitable corrugations or serrations corresponding in shape to the corrugations of the straining-bottom, and projecting up into the same, having a small space left between them. This beater is suspended by 55 means of rods d, passing through stuffing-boxes c in the sides of bottom of the tank, and these rods, and consequently the beater, may be reciprocated by having suitable pitman-connection between the ends of these rods and re- 60 volving eccentric-disks e, the beater shown in Figs. 1, 4, and 5 being reciprocated in a horizontal plane, while the beater shown in Fig. 3 is reciprocated in a vertical plane, having its serrations forced up toward the corrugations 65 in the straining-bottom and again drawn down.

Pipes b extend from the bottoms of the corrugations in the strainer and through suitable apertures or slots, i, in the beater and through the bottom of the tank, having suitable cocks, 70 h, at their lower ends, so that whatever collects in the bottoms of the corrugations may be drawn off through these pipes.

In Fig. 5 is shown a form of straining-bottom having the upper edges of the corruga- 75 tions extending up above the surface of the fluid in the tank, and having the said edges open, so that the spaces between the strainer and the corrugations upon the beater may be easily cleaned, and the strainer-sections may 80 be removed separately, while in the other forms shown the entire bottom must be removed for the purpose of cleaning or repairing it.

In all the forms shown from Figs. 1 to 5, in- 85 clusive, the corrugations run transverse to the tank; but they may run longitudinally to the tank, if desired, as shown in Figs. 6 and 7, when the beater is reciprocated transversely instead of longitudinally, as in the other forms. 90

It will be seen that by having the straining-bottom corrugated a larger straining-surface is gained in a comparatively small space, and that the reciprocating beater having its ribs or corrugations projecting up into the corruga- 95 tions of the strainer, it will continually beat the said strainer and prevent any objects from lodging in the apertures of the same. The fluids may be drawn off through the outlet, and whatever large objects remain upon the 100

strainer will fall to the bottoms of the corrugations, and may be either drawn off through the pipes or be otherwise removed.

Having thus described my invention, I claim
5 and desire to secure by Letters Patent of the
United States—

1. In a machine for straining or separating
solids from the fluids in which they are sus-
pended, the combination of a tank having a
10 straining-bottom formed with corrugations
with a beater having corresponding corruga-
tions or ribs projecting into the corrugations
of the straining-bottom and having means for
being reciprocated, as and for the purpose
15 shown and set forth.

2. In a machine for straining or separating
solids from the fluids in which they are sus-
pended, the combination of a tank having an

outlet at the bottom, a straining-bottom in the
tank having corrugations and formed with 20
downwardly-extending draw-off pipes pro-
vided with cocks, and a beater below the
straining-bottom, having corrugations or ribs
projecting into the corrugations of the strain-
ing-bottom and corresponding in shape to 25
them, and having apertures for the draw-off
pipes and having means for reciprocating it,
as and for the purpose shown and set forth.

In testimony whereof I hereunto sign my
name, in the presence of two subscribing wit- 30
nesses, this 29th day of October, 1886.

RUDOLF KRON.
